UNITED STATES PATENT OFFICE.

THOMAS W. SCOTT, OF BALTIMORE, MARYLAND, ASSIGNOR TO THE AMERICAN TRAIN CONTROL CO., OF BALTIMORE, MARYLAND, A CORPORATION OF MARYLAND.

AIR-BRAKE-CONTROLLING MECHANISM.

1,327,968.

Specification of Letters Patent. Patented Jan. 13, 1920.

Application filed December 17, 1915, Serial No. 67,374. Renewed November 12, 1919. Serial No. 337,621.

To all whom it may concern:

Be it known that I, THOMAS W. SCOTT, a citizen of the United States, residing at Baltimore, in the State of Maryland, have 5 invented certain new and useful Improvements in Air-Brake-Controlling Mechanism, of which the following is a specification.

This invention relates to an improved air-brake controlling mechanism, and is especially designed to coöperate with train-controlling mechanism of the automatic-stop type wherein the vehicle is automatically stopped in case the engineer or motorman proceeds in disregard of danger signals or 15 dangerous conditions ahead.

The present invention has to do, more particularly, with the operation of the air-brakes and one of its main objects is to provide an improved mechanism whereby after 20 the automatic stop mechanism has been actuated to apply the brakes the air-supply from the main reservoir shall be cut-off so that the train line cannot be recharged by any manipulation on the part of the engineer or motorman of the engineer's valve in 25 the cab until the train has been brought to a stop.

Another object of the invention is to provide an electro-pneumatic valve mechanism 30 that is interposed in the air-brake system between the main-reservoir and the engineer's valve, which pneumatic valve is itself controlled through a switch of a ramp-rail contact-shoe whereby to automatically cut-off communication between the main-reservoir and engineer's valve when an automatic 35 stop operation takes place.

A further object of the invention is to combine with an air-brake apparatus, an 40 electro-pneumatic valve to effect an automatic operation of the brakes, independently of the engineer's brake valve an electro-pneumatic valve to control the passage of air from the main reservoir to the engineer's valve and a shoe-operated switch to 45 control the two electro-pneumatic valves whereby when one valve effects an automatic operation of the brakes the other valve will cut-off the reservoir supply to the engineer's 50 valve and thus prevent recharging of the train line through the engineer's valve.

The drawings illustrate the invention, wherein,—

Figure 1, diagrammatically illustrates the apparatus.

Fig. 2, shows a sectional view of the train-line vent apparatus.

Fig. 3, shows in section, the device that controls the vent apparatus.

Fig. 4, is a sectional detail of the reservoir-pressure control device.

By referring to the drawing it will be noted that the numeral 1, designates the main reservoir; 2, the engineer's brake-valve and 3 the train line or brake pipe, all of the well-known air-brake equipment, of which the train line or brake pipe extends throughout the length of the train and has connections, as usual, through triple valves to the auxiliary reservoir and brake cylinders on the various cars, which triple valves, auxiliary-reservoirs and brake cylinders it is deemed unnecessary to illustrate.

In the present illustration, pipe connections 4, 5 and 6, are shown, between the main-reservoir 1 and engineer's brake valve 2, and a cut-off cock 7, is provided in the pipe connections 5, which cock is kept closed and sealed against use.

A pipe 8, branches from pipe 4, and leads to an electro-pneumatic valve casing 9, while another pipe 10, extends from said valve casing and connects with pipe 6, leading to the engineer's valve, thus pipes 8 and 10, provide a branch around the normally closed cock 7, so that main-reservoir air-pressure may normally pass through the electro-pneumatic valve to the engineer's brake valve.

The electro-pneumatic valve casing, briefly stated, has a passage 11, with which the pipe 8, connects and a port 12, is provided at the inner end of this passage through which the fluid pressure may pass to a chamber 13. The pipe 10, then leads from the chamber 13, to pipe 6. Directly beneath the port 12, the casing has an opening into which a valve-rod 14, projects and said rod has a narrow stem 15, that projects across the chamber; passes through the port 12, and carries a valve 16, at its outer end.

This valve 16, is thus retained in the passage 11, over the port 12, but is normally

raised so as to leave said port uncovered and allow air from the main reservoir and pipe 8, to pass through the chamber 13 to pipe 10.

The valve rod 14, has an armature head 17, at its lower end which latter is normally held up by the electro-magnet 18, so as to keep the rod 14, and the valve 16, at its upper end elevated as long as the magnet is energized.

10 In the present instance a resetting stem 19, is provided beneath the armature head 17, whereby a hand-resetting of the armature may be effected after the magnet has been deenergized.

15 In practice the electro-pneumatic valves employed in the operation of this invention are preferably located on the vehicle where they are inaccessible from the cab so that it is preferably necessary to bring the vehicle 20 to a full stop in order to gain access to these valves to reset them after they have been automatically operated.

25 The engineer's brake valve and the train line or brake pipe 3, are connected by a pipe 20, in which a cut-out cock 21, is usually placed, which cock, however is normally open.

30 The apparatus also includes an electro-pneumatic valve mechanism whereby to effect an automatic operation of the brakes independently of the engineer's valve which will now be briefly described.

35 A valve casing 22, has a passage 23, with a port 24, at the inner end thereof that opens into a chamber 25, and a pipe 26, connects the said passage 23, with the pipe 6, that supplies the main reservoir air. A normally-open valve 27, is provided in the passage 23, over the port 24, and said valve is 40 carried on a stem 28, that projects from the end of a valve-rod 29.

45 This valve-rod normally extends across and closes a passage 30, that leads to the atmosphere so that fluid pressure in the chamber 25, will be prevented normally from venting to the atmosphere through the passage 30. The rod passes through an electro-magnet 31, and carries an armature-head 32, at its lower end so that as long as 50 the magnet is energized the rod will be held up to keep valve 27, unseated and to close passage 30. A resetting stem 33, is also provided for the armature head 32, to reset the same after the magnet has been operated.

55 A pipe 34, extends from the chamber 25, and enters a chamber 35, in a casing and at the upper side of a diaphragm 36. Below the diaphragm the casing has another chamber 37, in which a valve 38, is located. This 60 valve is carried by a stem 39, that is attached to and moves with the diaphragm and the valve normally closes escape ports 40, that extend through the casing and also normally closes a port 41, at the inner end 65 of a pipe 42, which pipe connects with the

pipe 20, that communicates with the train-line or brake-pipe 3.

It will thus be understood that chamber 35, is normally subject to main-reservoir pressure from pipes 6 and 26 and chamber 25, while valve 38, is seated over port 41, and against the pressure in the pipe 42, that communicates with the train-line. If, therefore, the reservoir pressure is, say 90 pounds, and the train-line pressure is 70 pounds, the greater reservoir pressure on the upper side of the diaphragm 36, will hold stem 39 and valve 38, down on port 41, and against the lesser train-pipe pressure so this latter pressure cannot normally escape through the ports 40.

Under normal running conditions, both electro-magnets 18 and 31, will be energized through circuits that will now be explained.

In automatic stop devices of the character 85 herein referred to, the vehicle is provided with a contact shoe 43, which has a rod that carries or operates a shoe-switch 44, a current supply, such for example as a battery 45, is provided on the vehicle and a connection 46, extends from the positive side of the battery to one shoe-switch contact 47, while from the other switch contact 48, a wire or connection 49, leads to and connects with a binding post 50, of the electro-magnet 31. The other binding post 51, of this magnet has a return connection by wires 52, 90 53 and 54, to the negative side of the battery or current supply 45.

95 In a similar manner electro-magnet 18, 100 is energized from the vehicle current supply by a wire 55, that branches from wire 49 and is engaged with one binding post 56, and a return connection from post 57, and wire 58, to wire 53.

105 It will thus be seen that as long as the contact shoe 43, is down and shoe switch 44, is closed, both electro-magnets 18 and 31, will be energized, and the control of the brakes will be effected as usual through 110 the manipulations of the engineer's brake valve 2.

115 In practice the contact shoe 43, is positioned on the vehicle so it may engage ramp rails that are located at spaced-apart intervals along the trackway, and in the system in which the present invention is to form a part the ramp rails are connected with or disconnected from a track-way current supply (not deemed necessary to illustrate in 120 this case) according to the safe or dangerous conditions ahead.

125 If therefore, the contact shoe 43, engages an energized ramp it will pick up a current from that ramp and send the picked-up current through the two electro-magnets 18 and 31, and the return circuit will be by a wire 59, to and through the axle 60 and wheel 61; then through the track-rail back to the track-way current supply as is now well known in 130

this art. On the other hand, if the shoe 43, engages a deenergized ramp rail it will not pick up a current and during its upward movement in riding up onto the ramp rail it 5 will move shoe switch 44, so as to interrupt or break the connections in the normal vehicle circuit across contacts 44 and 48, thus cutting off both electro-magnets 18 and 31 from the vehicle current supply 45, and de- 10 energizing those magnets.

When magnet 31, is thus deenergized valve-rod 29, will drop and seat valve 27, to cut off the inlet of reservoir pressure and at the same time said rod 29, will uncover the pas- 15 sage 30, to the atmosphere so that the pressure in chamber 25, pipe 34, and chamber 35, over the diaphragm 36, will be vented to the atmosphere. The venting of the cham- 20 ber 35, at the upper side of the diaphragm 36, will produce a preponderance of pres- 25 sure on the valve 38, from the train line, consequently this latter valve will move up and the train line pressure will then escape from port 41, out through vent port 40, and 30 by this reduction in the train line pressure cause an application of the air-brakes, just the same as though the venting had taken place at the engineer's brake valve. Thus we get an automatic application of the brakes 35 independently of the engineer's brake valve.

As electro-magnet 18, is deenergized, valve rod 14, will drop and seat valve 16, on port 12, and thus prevent main reservoir air pressure from flowing through pipe 8 to the 35 engineer's brake valve; therefore without main-reservoir pressure, the engineer cannot, by any manipulations whatever of the engineer's valve, recharge his train line to release his brakes and he must bring his train 40 to a stop. Upon stopping his train, the engineer can then gain access to the reset de- vices 19 and 33, and reset the electro-magnets in order that he may reestablish the connec-

tion between the main-reservoir and engineer's valve, whereupon the brakes can be 45 released.

Having described my invention what I claim is,—

1. In an air-brake controlling mechanism the combination with an air brake apparatus including a reservoir, a train line and an engineer's valve, of connections for supply- 50 ing air from the reservoir to the train line only through the engineer's valve; one elec- 55 tro-pneumatic means entirely separate and independent of all the devices of the engi- 55 neer's valve for effecting an automatic ap- plication of the brakes, and a second elec- 60 tro-pneumatic means for cutting off the sup- 65 ply of all air to the train line to prevent a release of the brakes by the engineer.

2. In an air-brake controlling mechanism the combination with an air-brake apparatus including a reservoir, a train line and an engi- 65 neer's valve, of connections for supplying 70 air from the reservoir to the train line only through the engineer's valve; a valve con- 70 trolling the escape of air from the train line to the atmosphere; connections from one 75 side of said valve to the train line said con- 75 nections being entirely independent of the engineer's valve; connections from the other side of said valve to the reservoir to hold 80 the valve closed by reservoir pressure and these latter connections also being entirely independent of the engineer's valve; an elec- 80 tro-pneumatic valve in said latter connec- 80 tions and a second electro-pneumatic valve for cutting off all air to the train line to prevent a release of the brakes by the engineers.

In testimony whereof I affix my signature in the presence of two witnesses.

THOMAS W. SCOTT.
